FRONT EDGE DETECTOR MECHANISM

Headley Townsend Backhouse, Wentworth,
EnglandApplication August 10, 1948, Serial No. 43,427
In Great Britain August 5, 1947

4 Claims. (Cl. 271—56)

1

This invention comprises improvements in or relating to front edge detector mechanism for use in sheet feeding apparatus. The invention is concerned with sheet feeding apparatus of the kind in which sheets of paper or the like are removed in succession from a pile and fed on to a lay-board where, by means of lays or the equivalent, registration of the sheets is effected before they are transferred to a printing or other machine. In one form of such apparatus with which the invention is particularly, but not exclusively, concerned the sheets approach the lay-board in a continuous stream of partly overlapping sheets. Sheet feeding apparatus of this form are commonly known as stream-feeders. The invention comprises a feeler movably supported in the path of the sheets at or near the front lays and arranged for movement by each sheet in turn as the sheet approaches or reaches the front lays, and sensing mechanism operated in timed relationship with the sheet feeding mechanism for determining whether or not the feeler has been moved as aforesaid by a correctly placed sheet. In the preferred form of the mechanism the sensing mechanism is arranged, on sensing that the feeler has not been moved, for causing stoppage of the feeding of the sheets and/or the operation of a warning device.

It is an object of the present invention to improve the mechanism described in respect of the adaptability of the mechanism to sheet-feeding machines of varying dimensions.

The invention provides detector mechanism in which the feeler is carried on one end of a supporting arm which is attached at its other end to a fixed support member and which is variable in effective length (by a simple adjustment such as a sliding movement controlled by a thumb-screw) to enable the mechanism to be fitted to sheet feeding apparatus of different constructions and having lay-boards of different dimensions.

Preferably, the supporting arm is pivotally attached to the support member for partial rotation about a transverse horizontal axis and means are provided for rocking the supporting arm in timed relationship with the sheet feeding machine to lift the feeler upwardly from the lay-board to facilitate removal of each registered sheet in turn and then to return the feeler to the initial position to detect the arrival of the next sheet. The rocking means may comprise a follower on the supporting arm co-operating with a swinging cam surface on the aforesaid sensing mechanism.

The sensing mechanism may comprise an arm 55 ing drawings in which—

2

or the equivalent operated in timed relationship with the feeding of the sheets in combination with trip mechanism having a stop presented for possible engagement by the sensing arm during each forward movement thereof and on such engagement to restrict further movement of the arm but arranged to be withdrawn from said path on each movement of the feeler as aforesaid, the operation of the sensing mechanism being so timed that each sheet as it arrives at or approaches the lays in proper sequence causes the stop to be withdrawn before engagement with the sensing arm, but should a sheet be delayed or fail to feed the stop will engage the arm and cause the stoppage of the feeder or the operation of the warning device. When the invention is applied to the form of detector mechanism illustrated herein the trip mechanism may comprise a rotatably mounted shaft which is extensible in length and which is spring-urged for rotation about its major axis from a stop position in which a radial projection from the shaft, constituting the stop, lies in the path of the sensing arm and the shaft is retained in the stop position by the feeler or a part controlled by the feeler, until the feeler is moved by a sheet, whereby unless such movement of the feeler occurs at the appropriate time the stop engages and stops the sensing arm. Preferably, the shaft incorporates a torsionally locked telescopic joint, in order that it may be extensible. The feeler may comprise a pivoted arm arranged to be moved about its pivot by the sheets as they approach or reach the front lays and to constitute a latch securing a rocker which controls the spring-urged rotation of the shaft, the construction and arrangement being such that when the feeler is moved by a correctly placed sheet the rocker is released and allows the shaft to rotate to withdraw the stop from the path of the moving arm. The mechanism may include a resetting device operable to reset the shaft into the stop position between the feeding of successive sheets, and comprising a bell-crank of which one arm is arranged for engagement by the sensing arm near the end of the backward stroke thereof and the bell-crank is thereby given a movement of rotation about its pivot and the other arm is arranged on such rotation, to engage a cam or equivalent surface on the shaft and thereby to rotate the shaft into the stop position.

One specific form of the mechanism according to the invention will now be described by way of example and with reference to the accompany-

Fig. 1 represents diagrammatically a perspective view partly in section, of the mechanism before engagement of the feeler by a sheet, and

Fig. 2 represents diagrammatically a perspective view of a part of the mechanism, partly in section, in which the feeler has been engaged by a correctly placed sheet.

The example of the mechanism shown in the drawings is intended for use in a stream-feeder which feeds the sheets in partly overlapped formation on to a lay-board 33, having front lays 34 which, during the registration period, extend above the board to provide registration stops. The mechanism comprises a bracket 1 slidably mounted on a angle cross-bar 2 attached at its ends to the frame (not shown) and secured to said cross-bar by a clamping screw 3. The bracket has a rearward extension which is forked and embraces an oscillating shaft 32 to which is keyed a sensing arm 4.

A forward extension of said bracket carries on a pivot 14 a member 17 of inverted channel shape in which is slidably fitted a rectangular tube 18 which is slotted at 36 to receive a clamping screw 37 having a nut 16; the channel-shaped member 17 and the rectangular tube 18 together forming a pivoted extensible arm. A compression spring 15 depresses the forward end of this pivoted arm and causes an upward extension 35 on the rear of said arm to abut against a stop screw 5 which is housed in the bracket 1. The forward end of the tube 18 houses a feeler 26 normally suspended in a vertical position by a pivot pin 27, and a rocker 24 pivoted on a pin 25. A leaf spring 28 lightly urges the feeler 26 against an abutment 18b (shown in Fig. 2) formed by suitably cutting away the bottom wall of the tube 18. A bearing 23 is fixed in the tube 18 behind the rear end of the rocker 24 and a short shaft 22 which has a D-shaped head is journaled in said bearing and held against longitudinal displacement by means of a pin 29, and the flat on the D-shaped head is arranged to cooperate with the rear end of the rocker 24 in such a manner that rotation of the shaft 22 from the position shown in Fig. 1 will lift the rear end of the rocker. A square rod 20, fixed to the shaft 22, extends to the rear and is slidable in a square tube 19, the other end of which is fixed in a hollow shaft 11 rotatable in a bearing 13. A spiral spring 21 is secured at its inner end to the forward end of the rod 20. The outer end of the spring is secured to and reacts against one wall of the tube 18 thus tending to rotate parts 11, 19, 20 and 22 clockwise as viewed in the drawing.

At the rear end of the channel 17 the web is cut away leaving the two sides between which is mounted a bell-crank lever 7 pivoted on a pin 8. An adjusting screw 6 is fitted to the upwardly extending arm of the lever 7 and is arranged to abut against the rear face of a cam and stop piece 10 which is fixed to the arm 4. The horizontal arm of the bell-crank lever 7 has a flat upper surface arranged to cooperate with a flat on the rotatable shaft 11 and has its downward travel limited by a pin 9 secured to the sides of the channel 17. A pin 12 extends radially from the shaft 11 and is arranged to stop the forward motion of the cam and stop piece 10 when the shaft 22 is in the position shown in Fig. 1 (i. e. if the feeler 26 has not been moved by a correctly placed sheet). When the sensing arm 4 and the stop and cam piece 10 are at the rearward limit of their travel the screw 6 is adjusted so

that there is a slight clearance between the feeler 26 and the front end of the rocker 24, the rear end of said rocker being heavier than its front end. The feeler is therefore free to be moved by a correctly advanced sheet against the light pressure exerted on it by the leaf-spring 28 and without interference by the rocker.

The operation of the mechanism shown in Figs. 1 and 2 is as follows:

Starting from the Fig. 1 position when the feeler is moved forward by a correctly advanced sheet the abutment on its upper end is moved from under the forward end of the rocker 24, the leaf spring 28 yielding sufficiently to permit this action. The sensing arm 4 carrying the cam and stop piece 10 then moves forward thereby allowing the lever 7 to move and consequently allowing parts 11, 19, 20 and 22 partly to rotate under the action of the spring 21. By this rotation the pin 12, which has until this time been in the path of the stop piece on the cam 10, is moved out of said path and the rear end of the rocker 24 is lifted by the D-shaped head of shaft 22, so depressing the front end of the rocker and lifting the feeler above the path of the sheet in the manner illustrated in Fig. 2. Spring 28 is thereby placed under stress. The cam 10 continues to move forward and engages the roller 30 (supported by pin 31 in bearings in container 35) thereby depressing the rear end of the member 17 on which said roller is mounted and causing its front end, together with all the parts mounted on it to the fore of the pivot 14, to be lifted further from the sheet.

In the event of a sheet arriving late in the stream of sheets the feeler 26 is not moved to release the rocker 24 and parts 22, 20, 19 and 11 before the sensing arm 4 in its forward movement brings the stop piece 10 into engagement with pin 12 which arrests further movement of the arm 10 and causes the mechanism to stop by known means.

As the sensing arm 4 swings rearward the pressure of cam 10 against follower 30 is relieved and spring 15 lowers the forward end of channel 17. Immediately thereafter bell crank 7 is turned clockwise and through its camming action on the part 11 shaft 19, 22 is rocked back to the Fig. 1 position, whereupon spring 28 acts to snap rocker 24 and feeler 26 to their original positions shown in Fig. 1. The full tension of spring 21 is thereby restored and the parts are ready for the next cycle.

Having thus described my invention, I claim:

1. In sheet feeding apparatus of the kind described, a fixed support, an extensible supporting arm mounted upon and projecting forwardly from said fixed support, a feeler at the forward extremity of said supporting arm, a transverse oscillating shaft associated with said fixed support, a sensing arm fixed on said shaft, means carried by said supporting arm and comprising an element extending lengthwise of the arm and controlled by said feeler for stopping motion of said sensing arm and its shaft when the feeder fails to present a properly fed sheet to said feeler at the correct time in the cycle, and means for determining the effective length of said lengthwise element to correspond with different adjustments of said extensible support arm.

2. Apparatus as defined in claim 1, wherein said supporting arm is carried by a transverse pivot mounted on said fixed support and comprising means actuated by the oscillations of said sensing arm for swinging said supporting arm

on its pivot to lift said feeler above the sheet path during a portion of each cycle in which a properly fed sheet is presented to the feeler.

3. Apparatus as defined in claim 2, wherein the means for swinging said supporting arm comprises a follower on the supporting arm cooperating with a cam surface on the aforesaid sensing arm.

4. In sheet feeding apparatus of the kind described, a fixed support, an extensible supporting arm mounted upon and projecting forwardly from said fixed support, a feeler at the forward extremity of said supporting arm, a transverse oscillating shaft associated with said fixed support, a sensing arm fixed on said shaft, an extensible shaft rotatably mounted in said supporting arm and extending longitudinally thereof, said extensible shaft having a stop projection adapted to stand in the path of said sensing arm, means controlled by said feeler for holding said 10

projection in said path except when the feeler is tripped by a properly fed sheet, spring means functioning when said feeler is tripped for rotating said extensible shaft to remove said stop projection from the path of said sensing arm, and means actuated by the oscillations of said sensing arm in one direction for turning said extensible shaft to return said stop projection to the path of said sensing arm and to put said spring means under tension.
